(57) **CLAIM**

The ornamental design for a tripod for rescue, as shown and described.

DESCRIPTION

FIG. 1 is a perspective view of a tripod for rescue showing my new design;

FIG. 2 is a front view thereof;

FIG. 3 is a rear view thereof;

FIG. 4 is a top plan view thereof;

FIG. 5 is a bottom plan view thereof;

FIG. 6 is a left side view thereof;

FIG. 7 is a right side view thereof; and,

FIG. 8 is an isolated and enlarged view of a portion of FIG. 6.

In the drawings, the broken lines depict portions of the tripod for rescue that form no part of the claimed design.

1 Claim, 8 Drawing Sheets(56)
